UNITED STATES PATENT OFFICE

2,424,783

ROLLER SKATE REINFORCING PLATE

Robert R. Ware, Jr., Chicago, Ill., assignor to
Chicago Roller Skate Company, Chicago, Ill.,
a corporation of Arizona

Application January 5, 1945; Serial No. 571,390

4 Claims. (Cl. 280—11.19)

1
The present invention relates to a roller skate construction and more particularly to means for reinforcing a roller skate sole plate.

The present invention is more particularly directed to a skate of the type having resiliently supported axle mountings arranged to permit the axles to yield with respect to the body portion of the skate and to swivel about predetermined axes for shifting the wheels relative to the body of the skate to facilitate turning and control. In such construction a suitable yielding or cushioning connection is provided between the axles of the wheels or rollers together with a positive mechanical connection for limiting the yieldable movement of the axle assemblies in accordance with the predetermined plane.

In skates of this type, which are commonly permanently secured to the skating shoe, the more experienced skaters and the figure skaters put a great deal of strain upon the skates. For certain skating moves, it might also be desirable to provide a greater clearance between the body of the skate or the skating shoe and the wheels or rollers of the skate. It also would be desirable to provide a suitable reinforcement for the sole plate in such type of skate so as to better withstand the stress and strain to which the skate body is to be subjected. In order to provide such advantages without requiring a complete redesign of the components comprising such type of skate, which would necessarily make such improved structure relatively expensive, it is proposed in accordance with the present invention to provide a roller skate reinforcing plate to be inserted between the sole plate of the skate and the remainder of the skate which constitutes the rollers, axles, and interrelated parts.

It, therefore, is an object of the present invention to provide an improved skate construction comprising a roller skate reinforcing plate.

It is another object of the present invention to provide an improved roller skate reinforcing plate which will provide certain advantages over the arrangements of the prior art without necessitating complete redesign and reconstruction of the roller skate.

Other and further objects of the present invention subsequently will become apparent by reference to the following description taken in connection with the accompanying drawing wherein

Figure 1 is a side view of a roller skate provided with the present invention;

Figure 2 is a view of the bottom of the roller

2
skate as seen in the direction of the arrows along the step line 2—2 of Figure 1;

Figure 3 is an end view of the roller skate shown in Figures 1 and 2;

5 Figure 4 is a perspective view of the roller skate reinforcing sole plate comprising the present invention;

Figure 5 is a cross sectional view of the plate shown in Figure 4 as seen in the direction of the arrows along the line 5—5.

Referring to Figures 1, 2, and 3 in the drawing it will be seen that there has been shown a sole plate 10 of the type adapted to be secured to the sole of a skating shoe by any suitable means such as rivets or screws. Adjacent each end of the sole plate 10, there is provided a bracket such as the rear bracket 12 and a forward bracket 14 which is associated with pivotally and resiliently mounted wheels or rollers 16 and 18. Since both the forward and rear wheel assemblies are substantially identical in general form of construction, further description of such assembly will be limited to one of these assemblies.

The bracket 12 has a ball socket 20 which engages the ball end of an arm 22 connected at its other extremity to a suitable housing 24 which receives the roller or wheel axle 26. The housing 24 is provided with a flange 28 of such shape as to provide a cup-shaped recess for receiving a resilient cushion or buffer 30. The buffer 30 and the flange 28 are each provided with an aperture through which extends a bolt 32. The bolt 32 threadedly engages an embossment 34 which forms a part of the bracket 12. Immediately beneath the embossment 34 there is positioned one end of a strap 36 which cooperates with another strap 38 to provide a truss construction interconnecting the front and rear brackets and wheel assemblies. The strap 36 is retained in position by a jam nut 40. The upper strap 38 is suitably secured to the brackets 12 and 14. The structure thus far described generally corresponds to a type of skate structure common in the art and does not constitute a part of the present invention.

45 The foregoing structure, however, cooperates with the present invention to provide an improved skate structure of greater rigidity and more versatile manipulation by the skater. To provide such improved operation there is mounted between the sole plate 10 and the front and rear brackets 12 and 14 a reinforcing plate 42. Suitable rivets such as 44 interconnect in rigid relationship the reinforcing plate 42 with the body 10 and with the front and rear brackets 12 and 14. As may be seen from Figures 2 to 5 the

plate 42 has two similar end portions 46 and 48 which are substantially solid so as to provide adequate supporting and reinforcing surfaces to the brackets 12 and 14. The solid end portions 46 and 48 of the reinforcing plate 42 are interconnected by a plurality of ribs 50 arranged in the manner of beams so as to provide maximum longitudinal reinforcement and rigidity. The beams 50 are interconnected at the center by a cross member 52 so that the two end portions 46 and 48 are interconnected by a grid structure. Preferably the structure shown, which comprises the reinforcing plate 42, is one which is formed of a metal having suitable rigid characteristics such as forged steel. At the point where the members 50 and 52 cross, there is provided an apertured embossment 54 for receiving the upper end of a collared pin 56 which serves to interconnect the central portions of the truss straps 36 and 38. From the cross sectional view shown in Figure 5 it becomes apparent that the reinforcing plate 42 has appreciable height so that the sole plate 10 is elevated above the position which it would have were it connected directly to the end brackets 12 and 14. By virtue of this increased distance between the sole plate 10 and the roller 16 a greater clearance is provided for the pivotal action of the sole plate 10 relative to the plane of the rollers 16 thereby facilitating the manipulation and movement of the skate 30 by the more experienced skaters.

While for the purpose of showing and describing the present invention, a preferred embodiment has been shown in the drawing, it is to be understood that such modifications are contemplated as may be commensurate with the spirit and scope of the invention as set forth in the following claims.

This invention is hereby claimed as follows:

1. In a roller skate which includes a sole plate 40 adapted to be secured to a shoe, brackets respec-

tively secured to the ends of said sole plate, a plurality of rollers, means for supporting said rollers by said brackets in limited pivotal relation to said sole plate, a truss interconnecting said brackets and said supporting means, and connecting means extending between said truss and an intermediate portion of said sole plate, the combination therewith comprising an elongated reinforcing plate of substantial thickness disposed intermediate said sole plate and said brackets, said plate having solid end portions for backing said brackets and a ribbed intermediate portion above said truss, whereby said sole plate is both reinforced and elevated to increase the maneuverability of the skate.

2. The combination set forth in claim 1, wherein said reinforcing plate has flat upper and lower surfaces disposed in substantially parallel planes.

3. The combination set forth in claim 1, wherein said reinforcing plate is narrow in comparison with said sole plate.

4. The combination set forth in claim 1, wherein the intermediate portion of said reinforcing plate has a boss to receive the connecting means extending between said truss and said sole plate.
